CLAIM

The ornamental design for a computer case, as shown and described.

DESCRIPTION

FIG. 1 is a perspective view of a computer case showing our design.

FIG. 2 is a front elevational view thereof.

FIG. 3 is a left-side, elevational view thereof.

FIG. 4 is a right-side, elevational view thereof.

FIG. 5 is a top plan view thereof; and,

FIG. 6 is an enlarged view of the circled portion VI in FIG. 5. The broken lines shown in the drawings are included for the purpose of illustrating environmental structure and forms no part of the claimed design.
